HEAT FIXTURE

Paul O. Jordan, Hudson, Wis.

Application October 6, 1949, Serial No. 119,829

10 Claims. (Cl. 219—34)

1

The invention herein presents a heat fixture useful for various purposes but devised to be especially useful for warming outbuildings, such, for example, as farm milk houses.

The heat fixture is constituted as a hollow body supporting channel members with which heating lamps are assembled and providing a housing for lead wires to the heating lamps.

The object of the invention is to provide a heat fixture of the character as stated wherein will be incorporated simple, inexpensive, practical, efficient, novel and improved features of construction.

In the accompanying drawings forming a part of this specification;

Fig. 1 is a perspective view of a heat fixture made according to the invention as when applied to use;

Fig. 2 is an enlarged bottom plan view of the heat fixture;

Fig. 3 is an end elevational view, partially in section and partially broken away, of said heat fixture;

Fig. 4 is a longitudinal sectional view, taken on line 4—4 in Fig. 2;

Fig. 5 is a longitudinal sectional view, taken on line 5—5 in Fig. 3;

Fig. 6 is a transverse sectional view, taken on line 6—6 in Fig. 2;

Fig. 7 is a detail sectional view illustrating the manner in which channel members of the heat fixture are supported upon a hollow body there-of; and

Fig. 8 is a wiring diagram of an electrical system of the heat fixture.

Speaking generally, the new and improved heat fixture consists of a hollow body supporting channel members with which heating lamps of said heat fixture are assembled and providing a housing for lead wires of an electrical system in which said heating lamps are adapted to be connected. In practical use, the hollow body of the heat fixture ordinarily will be supported upon a building structure, as from a ceiling, denoted 10, such as the ceiling of a farm milk house or other outbuilding.

A hollow body of the heat fixture is constituted as a generally rectilinear member consisting of spaced, parallel, first and second base walls, indicated 11 and 12, respectively, spaced, parallel, opposite side walls 13, 13 and spaced, parallel, opposite end walls 14, 14. The side and end walls are perpendicular to each other and to the first and second base walls, and all of said side, end and base walls are joined at their locations of meeting.

2

The opposite side margins of the second base wall 12 terminate in equally spaced, parallel relation to the side walls 13, 13, thus to provide rectilinear openings 15, 15 at the opposite sides of said second base wall between said opposite side margins and said side walls spanning the distance between the end walls 14, 14. Opposite side portions of the second base wall extend inwardly of the hollow body and toward each other to provide interiorly projecting, oblique bounding walls 16, 16 at the opposite sides of an interior surface 17 of said second base wall.

Each of a pair of parallel channel members of the heat fixture is designated 18. It is to be understood, however, that a heat fixture made according to the invention can include a greater or less number of channel members.

Each of the channel members is constituted as an elongated base 19, spaced, elongated side walls 20, 20 extending away from opposite side edges of the elongated base, and spaced, parallel, end walls 21, 21 contiguous with the opposite ends, respectively, of the elongated base 19 and the elongated side walls 20, 20. The side and end walls of each channel member are in perpendicular relation to each other and to the elongated base, and each channel member is open at its side opposite its elongated base save for an overhanging flange 22.

The channel members 18, 18 are situated in the hollow body of the heat fixture with their elongated bases 19 and exterior portions of their elongated side walls 20, 20 and end walls 21, 21 disposed in or adjacent to the rectilinear openings 15, 15, and each channel member is supported upon said hollow body for rotative movement. More explicitly stated, each of the end walls 21 of each channel member 18 is supported upon a pivot element 23, disclosed as small screw bolts, situated in the adjacent end wall 14 of the hollow body, for rotative movement of the channel members in a plane perpendicular to the first and second base walls 11 and 12. The construction and arrangement will be such that while said channel members substantially fill the rectilinear openings 15, 15 they will be free for limited rotative movement in said hollow body. Each pivot element or screw bolt 23 has a slotted head disposed at the exterior side of the corresponding end wall 14 and supports a spring nut 24 to be engaged against the interior surface of the corresponding end wall 21. Lugs 25, one for each spring nut, struck interiorly from the end walls 21 are for precluding turning movement of the spring nuts. The end walls 21 are adapted to be frictionally grasped against the end walls 14,

thus to preclude rotative movement of the channel members, in response to turning home actuation of the pivot elements or screw bolts 23 after said channel members have been rotatably adjusted to any position relative to the hollow body of the heat fixture which may be predeterminedly selected. The construction and arrangement desirably can be such that when the elongated bases 19 of the channel members 18 are parallel to the first base wall 11 said elongated bases will lie in a single plane substantially aligned with the second base wall 12, as in Fig. 6 of the drawings.

Perforations 26 through the first base wall 11 are for receiving fastening means 27, screws as shown, for securing the heat fixture to a ceiling, such as 10, or to some other supporting structure.

The elongated bases 19 of the channel members 18 support heating lamps 28, and the interior surface 17 and oblique bounding walls 16, 16 of the hollow body of the heat fixture together provide a housing for lead wires to said heating lamps.

An end wall 14 of the hollow body suitably and conveniently supports an insulating bushing 29, disposed between and in spaced relation to the channel members 18 in aligned relation to the lead wire storage space provided by said interior surface 17 and oblique bounding walls 16, 16, providing an inlet for lead wires 30 to the interior of said hollow body. A switch for manually turning the electric current off and on is indicated 31, and a thermostat for controlling current to the heating lamps is denoted 32.

Each of the opposite end portions of the elongated base 19 of each of the channel members 18 detachably supports a receptacle 33 for a heating lamp 28. The receptacles 33 can be of duplicate construction and each can be assembled with its corresponding elongated base in the same manner as all of the others. As disclosed, each heating lamp receptacle is constituted as an insulating block 34 inside the corresponding channel member and a lamp receiving shell 49 projecting forwardly through an opening in the corresponding elongated base. An insulating nut 35, threaded upon the free end portion of an external surface of each shell and engaged against the forward surface of the corresponding elongated base, retains an annular shoulder of the corresponding insulating block in surrounding relation to the shell against the interior or rearward surface of said corresponding elongated base, thus to cause each receptacle to be made rigid with the elongated base by which supported. The insulating nuts 35 are threaded upon external surfaces of the shells, and the heating lamps 28 are threaded in internal surfaces of said shells in customary manner.

An incoming wire 36 from a source (not shown) of electrical energy extends to a first fixed contact element 37 of the thermostat 32, a second fixed contact element of said thermostat is denoted 38, and a movable contact element 39, adapted to bridge the fixed contact elements 37 and 38, is supported by a bi-metallic strip 40 of the thermostat.

A lead wire 41 extends from the fixed contact element 38 by way of lead wires 42 to each of the heating lamps 28, and lead wires 43 extend from each of said heating lamps to an incoming wire 44. The construction and arrangement will be such that the movable contact element 39 will become engaged with the fixed contact elements 37 and 38 in response to decrease in temperature and disengaged from said fixed

contact elements in response to increase in temperature.

The manually actuatable switch 31 includes a fixed contact element 45, with which the incoming wire 36 is conductively connected by a lead wire 46, and a movable contact element 47, conductively connected by a lead wire 48 with the lead wire 41.

All of the lead wires to the heating lamps 28 will be situated within the housing provided by the interior surface 17 and the oblique bounding walls 16, 16 of the hollow body of the heat fixture, upon said interior surface, and the channel members are open to said housing across the interior surfaces of the overhanging flanges 22, 22. Thus passageways for lead wires of the electrical system to the heating lamps are provided.

The channel members 18 of course are rotatably adjustable in the hollow body of the heat fixture, in the manner as hereinbefore set forth, to the end that heat from the lamps 28 can be directed toward different locations of a room or space equipped with the heat fixture which may be selected, it being a well known fact that more heat emanates directly forwardly from the outer end of a lamp bulb than sideways thereof. The heating lamps 28 are independently adjustable. In Fig. 3 of the drawings, the channel member at the left is at adjusted position to cause heating lamps when supported thereby to direct their heat vertically downward from the ceiling 10, and the channel member at the right is at adjusted position to cause heating lamps when supported thereby to direct their heat downwardly toward the left. Each of the channel members is capable of adjustment through an arc sufficient in extent to direct heat from lamps supported thereby toward distantly spaced locations of a room or space having the heat fixture.

What is claimed is:

1. In a heat fixture, a hollow body consisting of spaced first and second base walls and spaced side and end walls contiguous with said first and second base walls, opposite side margins of the second base walls terminating in spaced relation to said side walls to provide openings at the opposite sides of said second base wall between said opposite side margins and the side walls, channel members adjustably supported in the hollow body to be accessible at each of said openings, and heating lamp receptacles supported by said channel members each having a first portion thereof situated within and a second portion thereof situated exteriorly of said hollow body.

2. In a heat fixture, a hollow body consisting of spaced first and second base walls and spaced side and end walls contiguous with said first and second base walls, opposite side margins of the second base wall terminating in spaced relation to said side walls to provide openings at the opposite sides of said second base wall between said opposite side margins and the side walls, a channel member constituted as an elongated base, side walls and end walls situated in the hollow body in contiguous relation to each of said openings to be accessible exteriorly of said hollow body, means supporting each of said channel members upon said hollow body, and heating lamp receptacles supported by said channel members each having a first portion thereof situated within and a second portion thereof accessible exteriorly of said hollow body.

3. In a heat fixture, a hollow body consisting of spaced first and second base walls and spaced side and end walls contiguous with said first and

second base walls, opposite side margins of the second base wall terminating in spaced relation to said side walls to provide openings at the opposite sides of said second base wall between said opposite side margins and the side walls, a channel member constituted as an elongated base, side walls and end walls situated in the hollow body in contiguous relation to each of said openings to be accessible exteriorly of said hollow body, means supporting the end walls of each of said channel members upon the end walls of said hollow body for rotatable adjustment of the channel members, and heating lamp receptacles supported by the elongated bases of said channel members each having a first portion thereof situated within and a second portion thereof accessible exteriorly of said hollow body.

4. In a heat fixture, a hollow body consisting of spaced apart first and second base walls and spaced side and end walls contiguous with said first and second base walls, opposite side margins of the second base wall terminating in spaced relation to said side walls to provide openings at the opposite sides of said second base wall between said opposite side margins and the side walls, interiorly extending flanges upon said opposite side margins in spaced relation to said first base wall providing, together with said second base wall, a housing for lead wires, channel members adjustably supported in the hollow body to be accessible at each of said openings, and heating lamp receptacles supported by said channel members each having a first portion thereof situated within and a second portion thereof situated exteriorly of said hollow body.

5. In a heat fixture, a hollow body consisting of spaced first and second base walls and spaced side and end walls contiguous with said first and second base walls, opposite side margins of the second base walls terminating in spaced relation to said side walls to provide openings at the opposite sides of said second base wall between said opposite side margins and the side walls, interiorly extending flanges upon said opposite side margins providing, together with said second base wall, a housing for lead wires, a channel member constituted as an elongated base, side walls and end walls situated in the hollow body in contiguous relation to each of said openings to be accessible exteriorly of said hollow body, means supporting each of said channel members upon the hollow body, and heating lamp receptacles supported by said channel members each having a first portion thereof situated within and a second portion thereof accessible exteriorly of said hollow body.

6. In a heat fixture, a hollow body consisting of spaced first and second base walls and spaced side and end walls contiguous with said first and second base walls, opposite side margins of the second base wall terminating in spaced relation to said side walls to provide openings at the opposite sides of said second base wall between said opposite side margins and the side walls, interiorly extending flanges upon said opposite side margins in spaced relation to said first base wall providing, together with said second base wall, a housing for lead wires, a channel member constituted as an elongated base, side walls and end walls situated in the hollow body in contiguous relation to each of said openings to be accessible exteriorly of said hollow body, means supporting the end walls of each of said channel members upon the end walls of said hollow body for

rotatable adjustment of the channel members, and heating lamp receptacles supported by the elongated bases of said channel members each having a first portion thereof situated within and a second portion thereof accessible exteriorly of said hollow body.

7. In a heat fixture, a hollow body consisting of spaced first and second base walls and spaced side and end walls contiguous with said first and second base walls, a side margin of the second base wall terminating in adjacent relation to an adjacent side wall to provide an opening at a side of said second base wall between said side margin and said adjacent side wall, a channel member situated in the hollow body in contiguous relation to said opening to be accessible exteriorly of said hollow body, means supporting said channel member upon said hollow body, and a heating lamp receptacle supported by said channel member for rotatable adjustment relative to said hollow body and having a first portion thereof situated within and a second portion thereof accessible exteriorly of said hollow body.

8. In a heat fixture, a hollow body consisting of spaced first and second base walls and spaced side and end walls contiguous with said first and second base walls, a side margin of the second base wall terminating in spaced relation to one of said side walls to provide an opening at a side of said second base wall between the second base wall and the adjacent side wall, a channel member adjustably supported upon at least one of said end walls and in said hollow body to be accessible at said opening, and a heating lamp receptacle supported by said channel member having a first portion thereof situated within and a second portion thereof situated exteriorly of said hollow body.

9. In a heat fixture, a hollow body consisting of spaced first and second base walls and spaced side and end walls contiguous with said first and second base walls, a side margin of the second base wall terminating in spaced relation to one of said side walls to provide an opening at a side of said second base wall between the second base wall and the adjacent side wall, a channel member constituted as an elongated base, side walls and end walls situated in the hollow body in contiguous relation to said opening to be accessible exteriorly of said hollow body, means supporting said channel member upon at least one of the end walls of said hollow body, and a heating lamp receptacle supported by said channel member having a first portion thereof situated within and a second portion thereof accessible exteriorly of said hollow body.

10. In a heat fixture, a hollow body consisting of spaced first and second base walls and spaced side and end walls contiguous with said first and second base walls, a side margin of the second base wall terminating in spaced relation to one of said side walls to provide an opening at a side of said second base wall between the second base wall and the adjacent side wall, a channel member constituted as an elongated base, side walls and end walls situated in the hollow body in contiguous relation to said opening to be accessible exteriorly of said hollow body, means supporting said channel member upon the end walls of said hollow body for rotatable adjustment of the channel member, and a heating lamp receptacle supported by the elongated base of said channel member having a first portion thereof situated within and a second portion thereof situated within and a second por-

75

tion thereof accessible exteriorly of said hollow body.
